WESTINGHOUSE MACHINE COMPANY, A CORPORATION OF PENNSYLVANIA.

BLADE-SECURING MEANS.

1,046,390

Specification of Letters Patent. Patented Dec. 3, 1912.

Application filed April 10, 1911. Serial No. 620,027.

To all whom it may concern:

Be it known that I, FRANCIS HODGKINSON, a subject of the King of Great Britain and Ireland, and a resident of Edgewood Park, 5 in the county of Allegheny and State of Pennsylvania, have made a new and useful Invention in Blade-Securing Means, of which the following is a specification.

This invention relates to turbines, and 10 particularly to means for securing the bases or roots of blades to blade-carrying elements.

As is well known, turbine blades are subjected to considerable centrifugal force due 15 to the high rotative speeds at which turbines operate, and in certain types of blades, particularly those usually employed in connection with turbines of the Parsons type, the centrifugal force upon the blades 20 is liable to cause them to become loose, and, manifestly, a loose blade in a turbine is a very serious menace to the rest of the blades.

It is one of the objects of my invention 25 to provide a blade-securing means, which will efficiently hold the blades in place and prevent their becoming loose in the actual operation of the turbine.

In carrying out my invention, I preferably construct the blade of a strip of metal 30 drawn to blade shape and provide a lip or foot at the bottom thereof which may be formed by a die and bulldozer by upsetting the end of the blade. The upset root or foot of the blade is considerably stronger than 35 a bent-over portion would be, for, manifestly, the upsetting of the blade root forces the molecules of the metal closer together, and if desired the roots may be made of any thickness. The blade root is preferably 40 of less width than the width of the blade, so that it may fit into a groove in the wall of the ordinary turbine blade receiving groove. The thickness of the root is preferably that of the height of the wall of the 45 supplemental groove, so that the packing pieces may rest firmly upon the floor of the turbine groove and over the root of the blade so that these packing pieces need not be weakened or cut to receive the root. 50 The packing pieces are preferably inserted in undercut grooves and wedged in place so that they need not necessarily be calked in the grooves, but may be held in place by wedges so that in the event that some of 55 the blades need not be taken out for repairs,

or for other purposes, the wedges, packing pieces and blades may be removed with ease.

In the drawings forming a part of this specification, Figure 1 is a fragmentary perspective view of a blade-holding element 60 in which blades constructed in accordance with my invention are shown. Fig. 2 is a plan view of a portion of a blade-holding element showing the blades in place. Fig. 3 is a longitudinal sectional view on the 65 line 3—3 of Fig. 2. Fig. 4 is a perspective view of a blade showing the relation of the packing piece in dotted lines. Fig. 5 is a cross-sectional view of a blade-holding element in which a blade and packing piece are 70 secured, and Fig. 6 is a view of a slight modification.

Referring now to Fig. 1: 10 designates a blade-holding element provided with a groove 11 in which is a subjacent or supplemental groove 12 in the floor thereof. The sides of the groove 11 are preferably inclined as at 13 and 14 to provide under-cut portions for the respective packing pieces and wedges. 75

The blade is best illustrated in Fig. 4 and is shown as comprising a blade portion 15, having a foot or root 16 at one end thereof, which foot may be formed by being die-struck in a bulldozer so as to upset 80 the metal. In actual practice, the upsetting of the end of the blade may extend entirely across the blade, but portions of the root or foot may be cut away so that said foot will be narrower than the width of the 85 blade. In actual practice it is desirable that this foot shall be of approximately the width of the groove 12 and of approximately 90 the same thickness.

The manner of inserting the blades is best shown in Fig. 1 in which the blades are inserted in the groove 11 so that at least one over-lapping portion 17 will rest upon the floor of the groove 11, and the foot or tongue will be within the groove 12. If desired, the thickness of the root may be slightly less than the depth of the groove 12 so that a space 18 is provided between the bottom of the root and the floor of the groove 12 to allow for contraction and expansion of the root in actual practice. After the blade is put in place, a packing piece 19 is inserted which is of greater width than the width of the blade 15 and which has an inclined portion 20 fitting 110

within the undercut portion of the groove 11, formed by the side-wall 13. The opposite side of the packing piece 19 is preferably straight, as indicated at 21.

From an inspection of the drawings, Figs. 1, 2 and 5, it will be observed that a space is formed between the ends of the packing pieces, the blades and the side wall 14 of the groove 11. This space may be filled 10 by compound tapered wedges designated as 22 and 23, which force the packing pieces to engage the undercut side of the groove 11 and hold the blades in their proper operative position. It will be observed that 15 the tops of the roots of the blades are in approximately the same plane as the floor of the groove 11, so that the packing pieces may fit snugly over them and hold them in place. The packing pieces need not be 20 calked so as to contract them in engaging the undercut surface of the groove, but under certain conditions, it might be necessary to provide a slight calking to tighten up the relationship of the packing pieces 25 and their wedges. In no case, however, will the calking extend to causing the packing pieces to flow into the undercut portions of the groove 11. If the blades and packing pieces are held in place by wedges 30 the last of the packing pieces and blades may be put in in a manner common to the practice now generally employed. Under certain conditions the wedges need not be employed, but the supplemental groove will 35 be used with the blade having a foot or root of less width than the body portion of the blade. I may also employ a blade of inverted T-shape if desired, as shown at 15^a, Fig. 6.

40 From the foregoing, it will be apparent that the blades will be held readily in place and that any liability of them becoming loose or separated from their roots will be avoided, inasmuch as the blades are strongest at the roots. In actual practice it has 45 been found that blades secured in place in accordance with the structure and manner

heretofore set forth, have actually withstood a pulling strain to the extent that the blades have been drawn or pulled apart in 50 their body portions, while the roots have remained intact with the blade-holding element. Therefore, it will be seen that the blade and its securing means are both simple and efficient for the purpose intended. 55

In accordance with the provisions of the patent statutes, I have described the principle of operation of my invention, together with the device which I now consider to represent the best embodiment thereof, but 60 I desire to have it understood that the device shown is only illustrative and that the invention can be carried out in other ways.

Having thus described my invention, what I claim is:

1. The combination with a grooved blade-holding element having a subjacent groove in the floor of the first named groove, a blade having a foot or projection at one end thereof, the foot being of approximately 70 the same width as the width of the subjacent groove, and the blade being of greater width than the width of the subjacent groove, but less width than the width of the first named groove, a packing piece for 75 holding the blade in place and engaging an undercut portion of the groove, and wedges for holding the packing pieces in place.

2. The combination with a grooved blade-holding element having a groove in the floor 80 of the first named groove, a blade having a projection at right-angles to its body portion and resting in the second mentioned groove, packing pieces in the first mentioned groove for holding the foot of the blades in 85 place, and wedges for holding the packing pieces in their groove.

In testimony whereof, I have hereunto subscribed my name this 7th day of April, 1911.

FRANCIS HODGKINSON.
